Primary Examiner — Jennifer O King(74) *Attorney, Agent, or Firm* — McCoy Russell LLP(57) **CLAIM**

The ornamental design for an engine control unit, as shown and described.

DESCRIPTION

FIG. 1 is a perspective view of an engine control unit of a new design;

FIG. 2 is a front view thereof;

FIG. 3 is a first side view thereof;

FIG. 4 is a second side view thereof;

FIG. 5 is a top view thereof; and,

FIG. 6 is a bottom view thereof.

The broken line portion of the figure drawings is included to show unclaimed subject matter only and forms no part of the claimed designs.
